UNITED STATES PATENT OFFICE.

GEORGE W. GRAHAM, OF NEW YORK, N. Y.

DESIGN FOR GIMP.

SPECIFICATION forming part of Design No. 19,196, dated July 9, 1889.

Application filed May 23, 1889. Serial No. 311,881. Term of patent 7 years.

To all whom it may concern:

Be it known that I, GEORGE W. GRAHAM, of New York, in the county and State of New York, have invented a new and original Design for Gimp, of which the following is a specification.

This design consists, essentially, in the representation of a series of knots in a row along the center of the gimp. There are parallel lines represented on the sides of this row of knots.

The accompanying drawing represents a piece of gimp embellished with my design.

A designates a row of knot-shaped figures extending along the center of the gimp. They are here delineated as made out of a cord or thread much coarser than that forming the body of the gimp.

B C designate two lines, represented as broken lines, and extending lengthwise of the gimp on each side of the row of knot-shaped figures. These lines are coarse lines, and therefore prominent and conspicuous in the gimp.

What I claim as my invention, and desire to secure by Letters Patent, is—

A design for gimp, consisting of a row of knot-shaped figures extending centrally and two lines extending one at each side of the row of knot-shaped figures, substantially as shown and described.

GEORGE W. GRAHAM.
